UNITED STATES PATENT OFFICE

172,243

HELICOPTER TYPE TOY

Bruno Nagler, New York, N. Y.

Application July 12, 1952, Serial No. 20,600

Term of patent 14 years

(Cl. D34—15)

To all whom it may concern:

Be it known that I, Bruno Nagler, a citizen of the Republic of Austria and a resident of White Plains, county of Westchester, State of New York, U. S. A., have invented a new, original, and ornamental Design for a Helicopter Type Toy, of which the following is a specification, reference being had to the accompanying drawings, forming part hereof.

Figure 1 is a side elevational view of a helicopter type toy, showing my new design;

Figure 2 is a front elevational view thereof; Figure 3 is a perspective view thereof; and Figure 4 is a top plan view thereof.

I claim:

The ornamental design for a helicopter type toy, as shown.
